(57) **CLAIM**

The ornamental design for an electrode pad as shown and described.

DESCRIPTION

FIG. 1 is a top plan view of an electrode pad;

FIG. 2 is a bottom plan view thereof;

FIG. 3 is a front perspective view thereof;

FIG. 4 is a rear perspective view thereof;

FIG. 5 is a left side perspective view thereof;

FIG. 6 is a right side perspective view thereof; and,

FIG. 7 is a top view thereof in a state of use.

The bold dashed lines in the drawings depict portions of the electrode pad that form no part of the claimed design. The dotted lines depict environmental subject matter and form no part of the claimed design.
